DESIGN FOR A TOLL COIN OR TOKEN
DEVICE FOR AUTOMOBILES

Abraham Zitenfield and Joe Weil, New York, N. Y.

Application June 12, 1947, Serial No. 139,628

Term of patent 3½ years

(Cl. D52—4)

To all whom it may concern:

Be it known that we, Abraham Zitenfield and Joe Weil, citizens of the United States, residing at New York, in the county of New York and State of New York, have invented a new, original, and ornamental Design for Toll Coin or Token Device for Automobiles, of which the following is a specification, reference being had to the accompanying drawing, forming part thereof.

In the drawing

Fig. 1 is a front elevational view of a toll coin or token device for automobiles, showing our new design;

Fig. 2 is a bottom plan view thereof; and

Fig. 3 is a cross-sectional view taken substantially along the line 3—3 of Fig. 1.

We claim:

The ornamental design for a toll coin or token device for automobiles, substantially as shown.

ABRAHAM ZITENFIELD.

JOE WEIL.
